COIN WRAPPING DEVICE

Robert N. Bagley and Frank M. Ralston,
Eureka, Calif.

Application March 12, 1938, Serial No. 195,611

4 Claims.

(Cl. 93—2)

This invention relates to improvements in devices used to facilitate the wrapping of coins.

The present invention has for its primary object to provide an improved means for facilitating the application of wrappers to coins whereby such wrappers may be applied more conveniently than is possible by the present method of holding a stack of coins between two fingers while placing a wrapper thereabout, thus making it possible to wrap stacks of coins of any denomination with greater ease and with a consequent saving of time.

Another object of the invention is to provide a device for facilitating the application of wrappers to stacks of coins wherein interchangeable carriers are provided for holding coins of different denominations in a position, when grouped in a stack, which will enable the user of the device to apply a wrapper easily and quickly about the stack and to partially crimp the edges of the wrapper against the ends of the stack of coins before removing the coins from the carrier and then finish crimping after removal.

Still another object of the invention is to provide a novel means for holding a coin wrapper in position while it is applied to a stack of coins lying within the removable coin stack carrier or receptacle which forms a part of the device.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

40 In the drawing:

Figure 1 is a view in perspective of the device embodying the present invention showing thereon in dotted outline a coin wrapper.

Figure 2 is a sectional view taken on the line 45 2—2 of Figure 1 and showing, in addition, a coin wrapper on the device and in cross section, and a partly completed stack of coins disposed upon the wrapper and in the coin carrier.

Figure 3 is a sectional view taken through and 50 transversely of the device on the same line as Figure 2 but showing the coin receptacle removed.

Figure 4 is a sectional view taken longitudinally of the device through the top part only, upon the line 4—4 of Figure 1.

55 Referring now more particularly to the draw-

ing, the numeral 1 generally designates the body of the device embodying the present invention, which body may be of solid construction as illustrated, or might be of hollow form as may be found desirable, the general form or configuration of the body being immaterial so long as the same may be provided with the inclined or slanting top surface 2. This top surface is of elongated rectangular contour, conforming generally in outline with the contour of a coin wrapper 10 which it is intended to support, such a coin wrapper being illustrated in dotted outline in Figure 1 and indicated by the numeral 3. This same wrapper is shown in full lines and in working position in Figure 2.

Adjacent one end of the working surface 2 there is formed transversely of the surface a channel 4, the upper end of which is open as shown in Figure 3 while the lower end is closed by the wall 5.

The numeral 6 generally indicates a receptacle which is designed to be positioned in the channel 4 and to support a stack of coins of a given denomination. This receptacle comprises the elongated body portion 7 which has a top wall 8 which projects beyond the sides of the body 7 to form the supporting flanges 9. These flanges rest upon the surface 2 at the sides of the channel 4 when the body 7 is disposed within the channel as shown in Figure 4. Extending longitudinally of the wall 8 of the coin receptacle is a recess 10 which is substantially semicircular in cross section. This recess is of a diameter to receive a coin of one denomination and one end of the recess is partitioned by the wall 11 which has 35 extending from the top edge thereof of the coin supporting finger 12 which is directed longitudinally of and toward the opposite end of the recess.

The opposite end of the recess is open as indicated at 13 so that a stack of coins may be conveniently removed therefrom by being shifted longitudinally thereof across the top edge of the surface 2.

In practice there will be provided a group of 45 four coin receptacles in which the diameter of the channels 10 will vary to adapt the receptacles to coins of different sizes. For example, one receptacle will have a channel or recess of a diameter to receive pennies or dimes, another to receive nickels and quarters, the third to receive half dollars and the fourth to receive silver dollars. Each of these four receptacles will have the body portion 7 of the same width and length to fit snugly in the channel 4 and in all other 55

respects they will be the same except in the size of the recess 10.

At the longitudinal edges of the surface 2 between the channel 4 and the end of the surface 5 2 which is remote therefrom, spring clips 14 are provided which extend in and over the surface 2 and in spaced relation therewith so as to have the edges of a wrapper 3 easily inserted between them and the surface 2. The wrapper here illustrated 10 has one end cut to form a centrally located point 15 while at its other end it is cut obliquely as shown, and the wrapper is placed upon the surface 2 to lie across the recess 10 of a coin wrapper and with the pointed end adjacent the receptacle. 15

The coins to be wrapped are then laid on top of the wrapper over the recess 10 so that their weight will force the wrapper into the recess as shown in Figure 2 and after the required number 20 of coins has been placed in position with the bottom resting against the finger 12, the pointed end of the wrapper is turned over across the coins and the group of coins may then be easily rotated so that the wrapper will be made to envelop 25 the coins.

When the tapered end of the wrapper has been drawn beneath the clips 14 lying nearest the receptacle 6, the edges of the wrapper at the end of the group of coins may be folded in and 30 the rolling of the coins then completed. The finger 12 supports the group of coins above the end wall 11 of the recess 10 a sufficient distance to permit the turning in of the proper amount of wrapper to completely cover the coins.

35 It will be apparent, of course, that as coins of different denominations are stacked and rolled, the receptacle 6 will be changed to accommodate the particular coins to be wrapped and that the receptacles can be easily and quickly inserted and removed so that the changing of the same will involve only a very slight loss of time. As a result of the convenience afforded the person using the present device in wrapping coins, it has been determined experimentally that over 40 one minute is saved in counting and rolling a stack of coins by the use of the present device over the old method of holding between the fingers while rolling the stack in the wrapper. The present device also has the advantage over 45 the present used method of rolling coins, of making a tighter and firmer roll than it is possible to make when holding the coin stack in place between the fingers.

We claim:

55 1. A coin wrapping device comprising an elongated body having a flat top surface inclined transversely of the length and adapted to support a coin wrapper, said surface having a cut-out area transversely thereof adjacent one end, 60 a coin holding receptacle designed to position in said cut-out area and having a longitudinally extending upwardly opening coin receiving recess extending lengthwise of said area and means at one end of said coin receiving recess facilitating 65 the crimping of an edge of a wrapper against an end of a stack of coins in said recess.

2. A coin wrapping device of the character described comprising an elongated body having a coin wrapper supporting surface, said body having a slot transversely thereof adjacent one end of said surface, means at opposite edges of said surface for resiliently engaging and holding the longitudinal edges of a coin wrapper, and a coin supporting receptacle comprising a body adapted to fit into said cut-out area to lie across said surface, said body having a top wall provided with a longitudinally extending coin receiving recess and flanges extending longitudinally of said recess at the sides of the body, said flanges being adapted to lie upon said wrapper supporting surface and a finger at one end of said recess and directed longitudinally of the center thereof and toward the opposite end of the same. 10 15

3. A coin wrapping device of the character described, comprising an elongated body having a flat surface inclined transversely of the length 20 and provided adjacent one end with a transverse cut out area which is closed by a vertical wall across the lower end and which is open at its upper end, an elongated body adapted to position within said cut out area and to be supported 25 through contact at one end with said wall, said latter body having a longitudinally extending channel in its top face, a wall extending across the end of said channel which, when the last-mentioned body is in the cut out area, lies adjacent said first wall, the said inclined surface of the first body being designed to have a coin wrapper placed thereagainst to extend over the channel of the second-mentioned body, and a finger member integral with the wall at the end 30 35 of the second-mentioned body and extending longitudinally of said channel to support a stack of coins in spaced relation with the adjacent wall.

4. A coin wrapping device of the character described, comprising an elongated body having a flat surface inclined transversely of the length and provided adjacent one end with a transverse cut out area which is closed by a vertical wall across the lower end and which is open at its upper end, an elongated body adapted to position 40 within said cut out area and to be supported through contact at one end with said wall, said latter body having a longitudinally extending channel in its top face, a wall extending across the end of said channel which, when the last-mentioned body is in the cut out area, lies adjacent said first wall, the said inclined surface of the first body being designed to have a coin wrapper placed thereagainst to extend over the channel of the second-mentioned body, a finger 45 member integral with the wall at the end of the second-mentioned body and extending longitudinally of said channel to support a stack of coins in spaced relation with the adjacent wall, and resilient clip members disposed at the longitudinal edges of said surface at one side of the second-mentioned body for engagement over the longitudinal edges of a wrapper placed upon said surface. 50 55 60
